UNITED STATES PATENT OFFICE.

JOHN W. MINTON, OF WASHINGTON, PENNSYLVANIA

FLUSHING APPARATUS.

No. 818,185.

Specification of Letters Patent.

Patented April 17, 1906.

Application filed July 3, 1905. Serial No. 268,133.

To all whom it may concern:

Be it known that I, JOHN W. MINTON, a citizen of the United States of America, residing at Washington, in the county of Washington and State of Pennsylvania, have invented certain new and useful Improvements in Flushing Apparatus, of which the following is a specification, reference being had therein to the accompanying drawings.

10 This invention relates to certain new and useful improvements in flushing apparatus, and relates more particularly to a tank and valves for controlling the inlet and outlet of said tank.

15 The object of the present invention is to provide novel mechanism in connection with a tank for automatically controlling the inlet of water to said tank. To this end I have constructed a novel form of valve which is 20 actuated by a float, said valve being adapted to control the inlet of water to said tank. I have also devised a novel form of valve and valve-seat adapted to control the outlet of water from said tank, the last-named valve 25 being actuated in a manner common to flushing apparatus.

This invention has for its further object the provision of a flushing-valve-operating mechanism which will be positive in its action, 30 simple and inexpensive in its construction, and free from all danger of being broken from ordinary use.

With the above and other objects in view the invention finally consists in the novel 35 construction, combination, and arrangement of parts which will be hereinafter more fully described and then specifically pointed out in the claims, and referring to the drawings accompanying this application, like numerals 40 of reference designate corresponding parts throughout the several views, in which—

Figure 1 is a vertical sectional view of a flushing-tank constructed in accordance with my invention. Fig. 2 is a fragmentary vertical sectional view of an inlet-controlling valve. Fig. 3 is a top plan view of a bushing used in connection with the outlet-port of my improved tank. Fig. 4 is a detail perspective view of a portion of the float-operating 45 rod; and Fig. 5 is a top plan view of a portion of the tank, illustrating the valve controlling the outlet-port thereof.

Referring to the drawings, 1 designates a flushing-tank having an opening 2 formed in 50 its bottom, preferably near one end thereof, and in said opening is secured a vertically-

disposed water-inlet pipe 3, having an air-chamber 3^a, and the top of said pipe is flanged, as indicated at 3^b, to form a seat for a valve-casing 4. The lower end of the valve-casing is flanged, as indicated at 4^a, and a rubber gasket or washer 4^b is interposed between the valve-casing and the flanged end of the pipe 3, said casing being secured to the pipe 3 by suitable thumb-screws 4^c. The valve-casing 4 is provided in its upper and lower ends with compartments 5 and 6, said compartments communicating with one another by a central passage or bore 7. The top of the valve-casing is provided with a suitable form of stuffing-box 7^a, through which passes a rod 8, that portion of the rod passing through the bore or passage 7 being provided with radially-disposed wings 8^a, which guide the rod in its movement. 75

Upon the lower end of the rod is secured a ball 9, commonly known as a "Fuller" ball. This ball is adapted to engage a seat 9^a, formed in a glass or vitreous plate 10, which is held within the casing 4 by a brass retaining-ring 10^a. The top of the rod 8 is provided with a flat head 10^b, the object of which will be presently described. The compartment 5 is provided with an outlet-pipe 10^c, which extends within a short distance of the bottom of the tank 1. The valve-casing 4, diametrically opposite the outlet-pipe 10^c, is provided with an outwardly-extending bracket 12, carrying standards 14 and 15. Pivotedly mounted in the upper ends of the standards 15 is a lever 16, the one end of which rests upon the head 10^b of the valve-stem 8, as indicated at 17, while the other end of said lever is pivotally connected to a link 18, which is in turn pivotally connected to the shorter arm 19 of the rod 20, said rod being pivotally mounted in the upper end of the standard 14. The longer arm 21 of the rod 20 carries upon its end a spherical vitreous body 22, which serves functionally as a float. 95 100

The bottom of the tank 1 is provided with an opening 23, in which is mounted a flanged exterior screw-threaded bushing 24. The bushing 24 carries a spider-like frame 25, which supports a vertically-disposed pipe 21, that extends upwardly within the tank 1 and connects with the valve-casing 4, as indicated at 11, said pipe serving functionally as a guide and as a refilling-pipe. The top of the bushing 24 is beveled, as indicated at 27, and surrounding the opening 23 within the 105 110

22 tank I secure a resilient washer 28 and a plate 29 by bolts and nuts 30, which also serve to retain the bushing 24 within the opening 23 of the tank 1. The washer 28 extends downwardly into the beveled opening of the bushing 24 and forms a seat for a spherical body or globular valve 31, which is carried by a vertically-disposed pipe 32, which is slidably mounted upon the pipe 26, said pipe being mounted on the pipe 26 before it is connected to the valve-casing 4. The pipe 32 is provided with an adjustable clamp 33, carrying an outwardly-extending arm 34, that is connected to a pivotally-mounted operating-lever 35 by a link 36.

Secured to the plate 29 by one of the bolts 30 is an upwardly-extending curved rod 37, having a right-angular portion 38, which forms a seat for the arm 34, as will be presently described. The upper end of the rod 34 is secured to a bracket 37', carried by the upper edge of the tank 1. The longer arm 21 of the rod 20 is provided with an adjustable depending triangular-shaped member 39, having an angular or beveled side 40.

In connection with my improved flushing apparatus I preferably construct the valve 31 and the float 22 of glass, the spherical bodies being drilled or pierced to accommodate their respective supports, and in the employment of glass for valves I have reduced the expense incurred by manufacturing my improved flushing apparatus and have provided valves which will wear considerably longer than the ordinary type of valves, which are generally constructed of brass.

In operation when the operating-lever 35 is pulled the clamp 33, pipe 32, and valve 31 are elevated through the medium of the link 36. The elevating of the valve 31 causes the arm 34 of the clamp 33 to ride against the curved upwardly-extending rod 37, which causes the valve to partially turn the rod until the arm 34 reaches the right angular portion 38, when the same will be seated theron until released to allow the valve to descend to its seat. When the valve 31 has been raised, the water or fluid contained within the tank passes through the bushing 24 to the bowl or hopper, (not shown,) and the lowering of the float 22 opens the valve-ball 9 through the medium of the various levers carried by the valve-casing, and water is permitted to flow through the valve-casing into the tank. The lowering of the float 22 causes the depending member 39 of the rod 20 to engage the arm 34, the beveled or angular side 40 of said member 55 striking the arm and forcing it from its seat, at which time it descends and permits of the valve 31 closing the bushing 24 and retaining the water or fluid within the tank admitted by the valve within the valve-casing. The ascension of the float 22 closes the valve-ball

9, and the flushing apparatus is again ready to be used.

The slight turning or rotating of the valve 31 grinds all sediment and foreign ingredients from its seat, thus insuring a positive and effectual closure for the bushing 24. It will be observed that the depending member 39, clamp 33, and valves 9 and 31 can be easily adjusted to operate according to the amount of water it is desired to admit to the hopper or bowl.

While I have herein described the preferred manner of constructing my improved flushing apparatus, it is obvious that various changes may be made in the details of construction without departing from the general spirit and scope of the invention.

What I claim, and desire to secure by Letters Patent, is—

1. In a flushing apparatus, the combination with a tank having an inlet and outlet port, of a float-actuated valve controlling said inlet, said valve consisting of a casing having a discharge-pipe, a detachable vitreous valve-seat mounted within said casing, a valve operating in said casing, a globular vitreous valve controlling said outlet-port, means to elevate said valve, means to partially rotate and retain said valve in an elevated position, and means actuated by the first-named valve to release said valve, substantially as described.

2. In a flushing apparatus, the combination with a tank having an inlet and an outlet, of a float-actuated valve controlling said inlet, a globular vitreous valve controlling said outlet and elevated by the operation of a lever, means mounted adjacent to said outlet to partially rotate said valve when elevated, means to temporarily retain said valve in an elevated position, and means actuated by the first-named valve to release said valve, substantially as described.

3. In a flushing apparatus, the combination with a tank having inlet and outlet ports formed therein, of a float-actuated valve controlling said inlet-port, said valve consisting of a casing having a ball-valve operating therein, a vitreous valve-seat mounted in said casing, a globular vitreous float adapted to actuate said valve, a globular vitreous float controlling said outlet-port, a bushing mounted in said outlet-port, a refill-pipe carried by said bushing and said casing upon which said vitreous valve operates, means to elevate said valve, means to partially rotate and temporarily retain said valve in an elevated position; and means actuated by said float to release said valve, substantially as described.

4. In a flushing apparatus, the combination with a tank having inlet and outlet ports formed therein, of a float-actuated valve controlling said inlet, said valve consisting of a casing, a ball-valve mounted in said casing and actuated by said float, a globular vitre-

ous valve controlling said outlet-port, means to elevate said valve, means to partially rotate said valve when ascending and descending, said means being adapted to temporarily hold said valve in an elevated position, and means to release said valve, substantially as described.

In testimony whereof I affix my signature in the presence of two witnesses.

JOHN W. MINTON.
